UNITED STATES PATENT OFFICE.

RUFA E. PAGE, OF ITALY, TEXAS.

UNDERGARMENT.

Application filed January 11, 1927. Serial No. 160,339.

This invention relates to new and useful improvements in undergarments.

The object of the invention is to provide an undergarment in the form of a waist for supporting bloomers or the like and made so as to be slipped over the head of the wearer and being free from openings which must be buttoned or fastened to secure the waist about the body of the wearer.

10 A particular object of the invention is to provide a waist of the character described which may be economically produced by severing a strip from a bolt of goods, severing and utilizing the ends of the strip for shoulder straps and the intermediate portion of said strip for a continuous waist.

15 A further object of the invention is to produce a waist which will not need to be shaped and which may be finished by merely 20 turning hems along the top and bottom edges and sewing the ends together.

25 A particular object of the invention is to provide a tubular band or body having a section gathered from top to bottom and elastic strips applied to the top and bottom edges of the gathered section whereby the circular band is entirely expandable throughout its height and may be easily enlarged to 30 pass over the head and shoulders of the wearer.

A construction designed to carry out the invention will be hereinafter described, together with other features of the invention.

The invention will be more readily understood from a reading of the following specification and by reference to the accompanying drawings, in which an example of the invention is shown and wherein:

Fig. 1 is a perspective view of a waist constructed in accordance with my invention,

Fig. 2 is an enlarged cross-sectional view on the line 2—2 of Fig. 1,

Fig. 3 is an enlarged vertical sectional view on the line 3—3 of Fig. 1,

Fig. 4 is an enlarged vertical sectional view on the line 4—4 of Fig. 1, and

Fig. 5 is a plan view showing a bolt of goods and indicating in dotted lines how the waist is cut therefrom.

50 In the drawings the letter A designates a bolt or piece of goods having the usual selvage edges B. In forming a waist, a transverse strip is torn off, or severed, across the bolt on the line C'. This severed portion is then cut or torn at each end along the dotted lines D', which produces the body por-

tion C and the strap portions D, each of which latter has one selvage edge. The line C' is located from the end of the goods according to the vertical height of the waist to 60 be formed and the portions D will always be long enough to form the shoulder straps. The advantage of producing the parts C and D in this manner is that the weave of the goods possessing the greatest strength 65 will extend vertically of the waist and thus take the greatest strain.

In forming the waist, each strap D is folded upon itself, hemmed and stitched longitudinally along the hem by a line of 70 stitches 10, as is shown in Fig. 2. A hem 11 is turned at the top of the body C and the ends of the shoulder straps D are turned under with said hem, which is fastened by two rows of stitches 12 and 13 respectively. 75 A wider hem 14 is turned inward along the bottom edge and fastened by stitches 15. When the hem 14 is turned, strips of webbing 16 are inserted to reinforce the garment where the buttons 17 are attached. 80

The body C is fastened together at the rear by a vertical row of stitches 18, thus making a tubular or circular body which is continuous and which must be slipped over the head of the wearer in putting the same 85 on. It will be seen that the formation is very simple, there being no curves, darts or other shaped portions.

In order to make the waist expandable so that it may be stretched to pass over the 90 shoulders and to better fit the body of the wearer, the front portion of the body is gathered at 19. At the upper portion of this gather, a strip of elastic 20 is included between the stitches 12 and 13, said strip being 95 placed in the hem 11 when the latter is formed. The elastic strip has its ends fastened at the points where the shoulder straps enter the front of the waist, as is indicated at 22. A similar elastic strip 23 is secured 100 in the hem 14 at the bottom of the gathered panel 19, having its ends fastened at 24. The gathered panel extends the full height of the waist and the waist is equally expandable at any elevation, which makes it easy to 105 apply.

The waist being free from fastenings, reinforcements, or body tapes, is made light and comfortable. Its straight lines and simple construction make for economy, 110 which permits its manufacture at a low cost.

Various changes in the size and shape of

the different parts, as well as modifications and alterations, may be made within the scope of the appended claims.

What I claim, is:

- 5 A waist comprising a continuous body with overturned edges to form pockets and having an integral gathered section extending of equal width from its top to its bottom edge at the front of the body, elastic

strips extending transversely of the gathered sections and secured at their ends within the pockets at both the top and bottom edges, and opposite shoulder straps having their ends secured to the top of the body at the sides of the gathered front portion and the ends of the elastic strips. 10 15

In testimony whereof I affix my signature.
